UNITED STATES PATENT OFFICE

2,493,881

LIFTING GATE LATCH

Parks R. Ladd, Junction City, Ky.

Application August 25, 1948, Serial No. 46,119

1 Claim. (Cl. 292—66)

1

This invention relates to a lifting gate latch.

An object of the invention is the construction of an efficient gate latch, particularly adapted to farm gates, which will lift the outer end of the gate and hold it in its normal horizontal position when the gate latch is in a set condition.

Another object of the invention is the construction of an efficient gate latch that can be easily operated for locking or unlocking a gate.

A still further object of the invention is the construction of an efficient gate latch which is mounted in an accessible position to be easily operated from either side of the gate upon which the gate latch is mounted.

With the foregoing and other objects in view, this invention comprises certain novel constructions, combinations, and arrangements of parts as will be hereinafter fully described, illustrated in the accompanying drawings, and more particularly pointed out in the appended claim.

In the drawings:

Figure 1 is a view in side elevation of a farm gate shown in an unlocked position, with my gate latch attached thereto, while

Figure 2 is a similar view showing the gate latch in a set or locked position.

Figure 3 is an enlarged transverse sectional view, taken on line 3—3, Fig. 1, and looking in the direction of the arrows.

Referring to the drawings, in which the preferred embodiment of my invention is illustrated, 1 designates a farm gate that is hingely mounted in the usual way at 2, 2.

The gate latch comprises a sectional handle 3 and a substantially L-shaped or angular lever section 4. The lever section 4 comprises a body 5, which is bifurcated or slotted at 6, Fig. 3, for the purpose hereinafter specified. The slotted portion of said body 5 receives slat 7 of the farm gate 1. A bolt, or similar fastener, 8 extends through the bifurcated portion of body 5 and also through the slat 7, whereby the device is pivotally mounted on slat or bar 7. The bifurcated portion of the body 5 is provided with a plurality of horizontal apertures 8a, arranged in registering pairs for receiving bolt 8, whereby the lever section 4 is adjustably mounted on slat 7.

The sectional handle 3 comprises sections 9, 9. Each section is provided with an outwardly extending grip 10, which can be grasped by the operator during the operation of the device. A bolt 11, or similar fastening means, extends through the lower portion of the body 5 and also through the upper ends of sections 9, whereby the sectional handle 3 is pivotally mounted on the lever

section 4. A bolt, or similar fastening means, 12 extends through sections 9 and through the inner end of the latch bar 13, whereby the latch bar 13 is pivotally mounted on the sectional handle 3. The outer end of latch bar 13 is adapted to be placed upon pin 14 when the device is moved to its set position, as shown in Fig. 2. When the device is moved to its unset or unlocked position, as shown in Fig. 1, the latch bar 13 will be free of pin 14, thereby permitting the gate to be opened. It is to be noted that the latch bar 13 slides between two nails 13a and is retained in an unlatched position therebetween, Fig. 1.

Farm gates are usually comparatively heavy, and will more or less sag down, Fig. 1, when in their unlocked condition. Therefore, by employing my device, when the device is in its set or locking position, the gate will be lifted and held in its normal horizontal position, whereby the life 20 of the gate, as well as its efficiency, will be greatly increased.

It is to be noted that when in its set position, the gate latch has its sections 9 in an inclined position, towards the rear of the gate, whereby the 25 device is positively retained in its locked position. It is also to be noted that when in this locked position, the pivot, constituted by bolt 11, is not in the same vertical plane with the bolt 8; these 30 details, including the peculiar construction of the cooperating elements, produce an efficient lever device, whereby in locking the gate, the gate is lifted from the position shown in Fig. 1 to the position shown in Fig. 2.

A supplemental post or plate 15 is mounted on 35 post 16; this post or plate 15 carries the pin 14.

Another advantage for the angular structure 40 of body 5 is that it furnishes room for the inner end of latch bar 13 to move closely to the lever section, above the lower end of body 5, when the gate latch is in its set or locked position.

While I have described the preferred embodiment of my invention and illustrated the same in the accompanying drawings, certain minor changes or alterations may appear to one skilled 45 in the art to which this invention relates during the extensive manufacture of the same, and I, therefore, reserve the right to make such changes or alterations as shall fairly fall within the scope of the appended claim.

What I claim is:

A lifting gate latch comprising a lever section having an outstanding lower portion, a handle pivoted on the outer end of said outstanding lower portion, said handle being adapted to be swung 55 to an inclined position and partly over said lever

section and thereby be located in a locked or set position, and a latch bar pivotally mounted on said handle and being adapted to partly extend over said outstanding lower portion when said latch device is in a locked or set position.
